TOOTHBRUSH HOLDER

Maurice Perlin, Chicago, Ill.

Application July 30, 1948, Serial No. 41,680

3 Claims. (Cl. 312—207)

1

This invention relates to a tooth brush holder of the cabinet type adapted to hold a plurality of tooth brushes in dry sanitary condition and to protect them from dust.

Although the holder of the present invention is designed primarily for holding a plurality of tooth brushes, it will be apparent that it may be used for holding any articles of a similar nature. The bottom wall of the holder is curved to facilitate the positioning of the brushes therein. The holder is provided with a plurality of air vents and means to guide the flow of air across the faces of the brushes when the front wall is closed, to cause the bristles of each brush to be dried soon after it is replaced in the holder after use.

The holder of the present invention may be made from metal, but it is preferably made from a suitable plastic material, for example a synthetic resinous material either in a thermoset or thermoplastic state. Examples of the former resin are unsaturated alkyds and resins of the Bakelite type such as phenol-formaldehyde resin, and examples of the latter resin are polystyrene, polyethylene, polymethacrylate, a copolymer of vinyl chloride and vinyl acetate, etc.

The structure by which the above advantages are attained will be described in the following specification, taken in conjunction with the accompanying drawing, in which:

Figure 1 is a perspective view of a tooth brush holder embodying the invention, shown with the front wall open and a single brush positioned therein;

Fig. 2 is a longitudinal sectional view, taken generally along the line 2—2 of Fig. 1, but omitting the tooth brush and showing the front wall in closed position;

Fig. 3 is a cross sectional view, taken along the line 3—3 of Fig. 2;

Fig. 4 is a fragmentary cross sectional view through the hinge portions of the holder, showing them in disassembled relationship; and

Fig. 5 is a cross sectional view, taken along the line 5—5 of Fig. 4.

In the drawings, the reference numeral 2 indicates a back wall having integral flanges 3, 4, 5 and 6 extending rearwardly from its edges. Each flange is of the same depth so that the flanges will fit flush against the wall upon which the holder is supported and will space the back wall of the holder from the supporting wall to form an air space therebetween. A pair of hollow cylindrical projections 7 also projects rearwardly from back wall 2 a distance equal to

2

the depth of flanges 3, 4, 5 and 6. The opening in each projection 7 registers with an aperture 8 (Fig. 3) in back wall 2, so that screws 9, having their heads seated in apertures 8, may be driven into the supporting wall to secure the holder in place. Preferably the apertures 8 are counterbored to permit the heads of screws 9 to fit flush against back wall 2.

A bottom wall 10, integral with back wall 2, curves forwardly from a line substantially intermediate the height of back wall 2, as shown in Fig. 3. A plurality of rectangular apertures 11 is provided in bottom wall 10 in transversely spaced alignment. Each aperture 11 is large enough to 15 freely receive the handle H of one tooth brush, but is not large enough to permit the bristle end B to pass therethrough. Apertures 11 are located adjacent the bottom of the curved portion of bottom wall 10 to facilitate entry of each brush handle into one of the apertures. Even in the dark the user may hold a tooth brush handle against back wall 2 and when the tooth brush is moved downwardly the curve of bottom wall 10 will guide the handle to apertures 11. In order to 20 facilitate the seeing of apertures 11 in the dark, the edge portions around each aperture may be coated with any suitable luminescent material, as indicated at 11'.

Flange 6 has a pair of vertically spaced projections 12 and 13 extending towards the left, as seen in Fig. 1. The lower wall 14 of projection 12 and the upper wall 15 of projection 13 are notched, as indicated at 16 and 17, respectively, to form a hinge sleeve for supporting the front cover. A side wall 18 of the front cover, extending rearwardly from front wall 19, has a hinge lug 20 projecting therefrom. The length of lug 20 is slightly less than the vertical distance between walls 14 and 15 so that it will fit therebetween. A pair of pins 21 projects vertically from the top and bottom of lug 20 and fit into notches 16 and 17 to hinge front wall 19 to back wall 2. Although the single structure described is preferred, the specific hinge does not constitute part of the invention, and front wall 19 may be hinged to back wall 2 in any suitable manner.

In addition to side wall 18, front wall 19 also has a similar side wall 22 and a top wall 23 integral therewith. An integral flange 24 extends rearwardly from the lower edge of front wall 19 and inwardly from side walls 18 and 22. When front wall 19 is closed, as shown in Figs. 2 and 3, the rear edges of side walls 18 and 22 and top wall 23 abut the exposed face of back wall 2.

Side wall 22 has an ear 25 projecting therefrom. Ear 25 frictionally engages flange 4 to hold the front of the holder in closed position. Flange 4 is provided with a pair of reinforcing ribs 26 spaced adjacent opposite edges of ear 25 to stiffen the area of flange 4 engaged by ear 25 and to guide the ear to the proper closing position of the front cover. A finger piece 27 projects outwardly from side wall 22 at right angles to to facilitate opening the front of the holder.

When the front of the holder is in closed position the portion of flange 24 extending rearwardly from the lower edge of front wall 19 does not reach the forward edge of curved bottom wall 10 and thus leaves an air space therebetween. Flange 24 is also spaced below the forward edge of bottom wall 10. Flange 3, extending rearwardly from the top edge of back wall 2, is notched to provide a plurality of air vents 28. Back wall 2 is also provided with a plurality of slots 29 forming air vents positioned above the area normally occupied by the bristle ends of the tooth brushes housed in the holder. A fin 30 extends rearwardly from back wall 2 a distance equal to the depth of flanges 3, 4, 5 and 6. Fin 30 is located below air vents 29 and extends transversely across the entire width of back wall 2.

In addition to reinforcing back wall 2, fin 30 closes the air space behind back wall 2 and forces air entering vents 28 to flow through vents 29 and across the faces of brushes housed in the holder when the front of the holder is closed. The air flowing through vents 28 and 29 also flows through apertures 11 and the air space between flange 24 and bottom wall 10; or the flow of air may be in a reverse direction. The circulation of air caused by the ventilation of the holder constantly serves to dry the bristles and thereby keeps the tooth brushes in better condition for use.

Although I have described a preferred embodiment of my invention in considerable detail, it will be understood that the description is intended to be illustrative, rather than restrictive, as many details may be modified or changed without departing from the spirit or scope of the invention. Accordingly, I do not desire to be restricted to the exact structure described.

I claim:

1. A tooth brush holder comprising a back wall, rearwardly extending flanges adapted to fit against a wall upon which the holder is supported, an apertured bottom wall projecting forwardly from said back wall, a front wall, a pair of side walls projecting rearwardly from said front wall, one of said side walls being hinged

to said back wall, said front wall leaving an air space between its lower edge and the forward edge of said bottom wall when in closed position, a fin projecting rearwardly from said back wall and extending substantially across the width of said back wall, said fin being of the same depth as said flanges, and a plurality of air vents extending through said back wall above said fin.

2. A tooth brush holder comprising a back wall, rearwardly extending flanges adapted to fit against a wall upon which the holder is supported, an apertured bottom wall projecting forwardly from said back wall, a front wall, a pair of side walls projecting rearwardly from said front wall, one of said side walls being hinged to said back wall, said other side wall being frictionally engageable with said back wall to hold said front wall in closed position, said front wall leaving an air space between its lower edge and the forward edge of said bottom wall when in closed position, a fin projecting rearwardly from said back wall and extending substantially across the width of said back wall, said fin being of the same depth as said flanges, and a plurality of air vents extending through said back wall above said fin.

3. A tooth brush holder comprising a back wall, a front wall having integral side walls projecting rearwardly therefrom, one of said side walls being hinged adjacent one edge of said back wall, a plurality of flanges extending rearwardly from the edges of said back wall to fit flush against a wall upon which said holder is supported, a fin equal in depth to the depth of said flanges projecting rearwardly from said back wall and extending across the width of said back wall, the flange extending rearwardly from the upper edge of said back wall being notched to provide a plurality of air vents, and a plurality of air vents extending through said back wall above said fin.
